DESIGN FOR A TRANSCRIBER LISTENING DEVICE

Robert L. Stone, Guilford, Conn., and Earl F. Rutan, New York, N. Y., assignors to The Soundscriber Corporation, New Haven, Conn., a corporation of Connecticut

Application March 27, 1946, Serial No. 127,980

Term of patent 14 years

(Cl. D26—14)

To all whom it may concern:

Be it known that we, Earl F. Rutan, a citizen of the United States, and residing in the city of New York, county of New York, and State of New York, and Robert L. Stone, a citizen of the United States, and residing in the town of Guilford, county of New Haven, and State of Connecticut, have invented a new, original, and ornamental Design for Transcriber Listening Devices, of which the following is a specification, reference being had to the accompanying drawing, forming part thereof.

Fig. 1 is a side view of the transcriber listening device, showing our new design.

Fig. 2 is an end view of the same, taken along the line 2—2 of Fig. 1.

Fig. 3 is a sectional view taken along the broken

line 3—3 of Fig. 1, looking in the direction of the arrow.

Fig. 4 is a fragmentary end view taken along the broken line 4—4 of Fig. 1.

We claim:

The ornamental design for a transcriber listening device, as shown,

ROBERT L. STONE.
EARL F. RUTAN.
